UNITED STATES PATENT OFFICE.

CHARLES A. FOSDICK, OF KEOKA, IOWA.

BROOM-BRIDLE.

1,214,447.

Specification of Letters Patent. Patented Jan. 30, 1917.

Application filed October 25, 1916. Serial No. 127,653.

To all whom it may concern:

Be it known that I, CHARLES A. FOSDICK, a citizen of the United States, residing at Keota, in the county of Keokuk, and State of Iowa, have invented certain new and useful Improvements in Broom-Bridles; and I do hereby declare the following to be a full, clear, and exact description of the invention, such as will enable others skilled in the art 10 to which it appertains to make and use the same.

This invention relates to broom bridles, and the object of the invention is the provision of a simple, durable and practical bridle that can be cheaply manufactured and conveniently associated with a broom head, and when in operative position will effectively reinforce the broom straws, so as to admit of the straws retaining their rigidity throughout the life of the broom head.

Other objects will appear and be better understood from that embodiment of the invention of which the following is a specification, reference being had to the accompanying drawing forming a part thereof, in 25 which:

Figure 1 is a side elevation of a broom head with the improved bridle associated therewith, Fig. 2 is an edge view of the 30 broom head with the bridle mounted thereon, and Fig. 3 is a perspective view of the bridle detached from the broom head.

Referring to the drawing in detail, the letter A designates a broom head of ordinary construction, and the letter B designates, as an entirety, the improved bridle.

As shown in Fig. 3 of the drawing the bridle is formed of a pair of rectangular shaped frames 1 and 2 that are positioned 40 at intersecting planes. Adjacent sides of the frames 1 and 2 are pivotally connected by means of pivot pins 3. The frames 1 and 2 coöperate to provide clamping jaws, which, when the bridle is in operative position on 45 the broom head, crowds the straws forming the broom head so as to increase the rigidity of the straws, so that the straws will not easily bend or break from use, or when they

are wet. Substantially oval shaped loop members encircle adjacent sides of the frames 1 and 2 at points above the pivot 3, and are slidably associated with the sides of the frames. Those sides of the frames which have the loops 4 associated therewith are provided with notches 5 which are 55 adapted to interchangeably receive the loops 4, so as to hold the frames in different adjusted positions. In positioning the bridle on the broom head the frames 1 and 2 are moved to positions where they will extend, 60 substantially, at right angles to each other. The broom head is then inserted between the frames, as shown in Figs. 1 and 2, and the frames are then moved in the direction of each other so that they will clamp the 65 broom head therebetween. The loops 4 are then adjusted upwardly so as to further move the frames toward each other and cause the same to crowd the broom straws forming the head, and the loops 4 are then 70 engaged in certain of the notches so as to prevent the frames from having pivotal movement in a direction away from each other. The frames 1 and 2 provide clamping jaws that will give a maximum clamping action and by virtue of the employment of the loops 4, and the provision of the notches 5, the frames 1 and 2 can be held in 75 different clamping positions.

Having thus described my invention what I claim as new, is:

A broom bridle consisting of a pair of intersecting rectangular shaped relatively movable clamping frames, certain adjacent sides of the frames having pivotal connection with each other, and means adjustably associated with the clamping frames for holding the frames in different clamping positions.

In testimony whereof I affix my signature 90 in presence of two witnesses.

CHARLES A. FOSDICK.
